DRAG BUCKET AND CLEVIS THEREFOR

George W. Mork, South Milwaukee, Wis., assignor
to Bucyrus-Erie Company, South Milwaukee,
Wis., a corporation of Delaware

Application January 8, 1937, Serial No. 119,559

11 Claims.

(Cl. 37—135)

My invention relates to new and useful improvements in drag-buckets and clevises therefor.

The conventional drag-bucket, for use on what is known as a "dragline" excavator, is a boxlike structure open at the top and the front end. On the bottom, set back somewhat from the front, is a digging lip, carrying a row of digging teeth. A hoist chain, forking and attached to a trunnion on each side behind the center of gravity, supports the bucket. A drag chain, forking and attached to a clevis on each side of the front, drags the bucket through the earth which is being excavated. Several alternative points of attachment are frequently provided for this clevis; so that, by altering the line of pull of the drag-chain, the angle of incidence of the digging teeth to the ground can be correspondingly altered.

An arch spans the open top of the bucket near the front thereof.

Shortly above its point of forking, the hoist chain carries a forwardly projecting sheave. A chain running from the top of the arch, back and over this sheave, and thence to the point of fork of the drag chain, serves during hoisting to hold the bucket level, and thus prevent dumping, so long as this chain is held taut by tension on the drag chain.

It is believed that this conventional construction is familiar to the art, but for further details thereof, reference is now made to U. S. Patent No. 1,974,426, to W. Lehman, dated September 25, 1934.

It is the principal object of my invention to provide an improved clevis for the above assembly, together with the improvement of the cooperating portion of the bucket proper. More particularly it is my object to provide a clevis which will be easily adjustable to effect change of digging-angle, and which will be strong and firmly attached, and which will protect the bucket proper against wear. Furthermore it is desirable that these features be adapted to a clevis having a vertical swivel. In addition to my principal object, above stated, I have worked out a number of novel and useful tails, which will be readily evident as the description progresses. My invention consists in the novel parts and the combination and arrangement thereof, which are defined in the appended claims, and which three embodiments are exemplified in accompanying drawing, which are hereinafter particularly described and explained. Throughout the description, the same refer-

ence number is applied to the same member or to similar members.

Figure 1 is a side elevation of one form of my clevis, and of the cooperating portion of my bucket.

Figure 2 is a side elevation of a second form of my clevis, and of the cooperating portion of my bucket.

Figure 3 is a plan view of the device of Figure 1, taken along the line 3—3 of Figure 1, and 10 showing part of the bucket proper in section.

Figure 4 is a side elevation of a third form of my clevis, and of the cooperating portion of my bucket.

Referring now to Figures 1 and 3, it will be seen that 11 is the side-plate of my bucket. Onto this is secured by bolts 12 (or by rivets, welding or other equivalent means; or the part might even be built integral) a clevis-plate 13, preferably reinforced by ribs 14, and having a cylindrical vertical hole 15 in a part 16 which projects beyond the side-plate 11. The clevis-plate 13 is preferably bifurcated to straddle the side-plate 11, as shown in Figure 3.

17 is a clevis, having a transverse hole 18 for engaging the drag chain (not shown), and having two vertical holes 19 in projections 20, which straddle the projecting part 16 of the clevis-plate 13.

Through vertical holes 19 in the clevis, and 30 hole 15 in the clevis-plate, is inserted a pin 21, secured in place by a cotter-pin 22.

The device in Figure 2 is similar except as will appear from differences in the following description. 11' is the side-plate of my bucket. 35 Onto this is secured by bolts 12' (or by rivets, welding or other equivalent means; or the part might even be built integral) a clevis-plate 13', preferably reinforced by ribs 14', and having a cylindrical vertical hole 15' in a part 16' which 40 projects beyond the side-plate 11'. The clevis-plate 13' is preferably bifurcated to straddle the side-plate 11' as was shown in Figure 3.

17' is a clevis, having a transverse opening 18' for engaging the drag-chain (not shown), and 45 having two vertical holes 19' in projections 20', which straddle the projecting part 16' of the clevis-plate 13'. Opening 18' communicates clear through to the right, thereby enabling this form of my clevis to be inserted through an unbroken 50 link of my drag-chain. Within this opening 18' there is a protruding portion 23', for the purpose of confining the chain to a definite part of the opening 18'.

Through vertical holes 19' in the clevis, and 55

hole 15' in the clevis-plate, is inserted a pin 21', secured in place by a cotter-pin 22'.

The device in Figure 4 is similar to that in Figure 2 except as will appear from differences in the following description. 11' is the side-plate of my bucket. Onto this is secured by bolts 12' (or by rivets, welding or other equivalent means; or the part might even be built integral) a clevis-plate 13' preferably reinforced by ribs 14', and 10 having a cylindrical vertical hole 15' in a part 16' which projects beyond the side-plate 11'. Clevis-plate 13' is preferably bifurcated to straddle the side-plate 11', as was shown in Figure 3.

17' is a clevis, having a transverse opening 18' 15 for engaging the drag-chain (not shown). Opening 18' communicates clear through upwardly, thereby enabling this form of my clevis to be inserted through an unbroken link of my drag-chain. Within this opening 18' there is a protruding portion 23' for the purpose of confining the chain to a definite part of the opening 18'.

One arm 24' of the clevis passes through vertical hole 15' in the clevis-plate, to serve as a pivot for the clevis therein. A ring 25' is placed over the two arms of the clevis, this ring being held in place by cotter-pins 22', and thus serves both to close the opening of my clevis and to restrain it from slipping out of my clevis-plate.

It will be noted that, in all three embodiments 30 of my invention, two levels of attachment of the drag chain are selectively attainable, by simply reversing the clevis. Also that there is but one long strong place of swiveling attachment. Also that some part of the replaceable 35 relatively inexpensive clevis always lies below the projecting portion 16 of the bucket, and thus protects it from ground-engaging wear.

Reverting now for a moment to Figure 3, I shall describe two important features of my 40 clevis-plate 13. This plate is split clear through to the hole 15, by the slot 26, and is provided with abutments 27, to bear against the edge of the side plates 11 of the bucket. The slot 26 enables the clevis-plate to be sprung onto the 45 side plates, and thus give a tight fit without machining. The abutments 27 relieve the bolts 12 of the shear due to the bucket landing on its nose, which always occurs during each digging cycle.

Having now described and illustrated three 50 forms of my invention, I wish it to be understood that my invention is not to be limited to the specific forms or arrangements of parts hereinbefore described, except insofar as such limitations are specified in the appended claims.

55 I claim:

1. Means for attaching the drag chain to a drag bucket, comprising: a clevis plate projecting forwardly from the side of the bucket, and having a cylindrical substantially vertical hole, two flat portions to straddle the side-plate of the bucket, a slot extending rearwardly from the hole whereby the two flat portions are completely separated from each other throughout, and at least one projection extending inwardly from one 65 of the flat portions and bearing against the front edge of the side-plate; and a clevis assembly, having a cylindrical portion insertible in said hole for swiveling therein, means to secure this portion in place, a transverse hole for engagement with the drag chain, and means to positively confine the chain against vertical shifting while in this last-named hole; the last-named hole being so located in the assembly that a reversal of the assembly will move the hole to a materially 70 different level with respect to the bucket.

2. Means for attaching a drag chain to a drag bucket, comprising: a lug projecting forwardly from the side of the bucket; a U-shaped clevis, the feet of which have provision for swiveling attachment to the lug, and the U of which has a projection, in cooperation with the forward edge of the lug, for positively confining a cooperating chain-link (not claimed) to a position substantially nearer to one leg of the U than to the other; and means for swivelly attaching the 10 clevis to the lug.

3. Means for attaching a drag chain to a drag bucket, comprising: a lug projecting forwardly from the side of the bucket; a U-shaped clevis, the feet of which have provision for swiveling 15 attachment to the lug, and the U of which has a projection, in cooperation with the forward edge of the lug, for positively confining a cooperating chain-link (not claimed) to a position substantially nearer to one leg of the U than to the other; and means for swivelly attaching the clevis to the lug; the clevis being further characterized by the fact that a portion of it will underlie the entire lug to take the ground-engaging wear.

4. A clevis, comprising: two legs, terminating in feet having aligned holes therethrough; a U-shaped portion, for the reception of a cooperating chain-link (not claimed); and a projection of sufficient length as compared with the legs 30 so that, in cooperation with the attaching portion of the bucket (not claimed), it will serve to positively confine the cooperating chain-link to a position substantially nearer one leg than the other.

5. A clevis, comprising: two legs, terminating in feet having provision for attachment to a drag-bucket; a U-shaped portion, for the reception of a cooperating chain-link (not claimed); and a projection of sufficient length as compared 4 with the legs so that, in cooperation with the attaching portion of the bucket (not claimed), it will serve to positively confine the cooperating chain-link to a position substantially nearer one leg than the other.

6. A clevis, comprising: two legs, terminating in feet having provision for attachment to a drag-bucket; a U-shaped portion, for the reception of a cooperating chain-link (not claimed); and a projection of sufficient length as compared with the legs so that, in cooperation with the attaching portion of the bucket (not claimed), it will serve to positively confine the cooperating chain-link to a position substantially nearer one leg than the other; the clevis being further characterized by the fact that a portion of it will underlie the attaching portion of the bucket to take the ground-engaging wear.

7. A clevis assembly, comprising: two legs, one of which is adapted to be swivelly inserted in a hole on a drag-bucket (not claimed); a U in the other leg, for the reception of a cooperating chain-link (not claimed); a projection, in cooperation with the forward edge of the bucket for positively confining this link to a position substantially nearer the level of one end of the swiveling portion than of the other end; and means for simultaneously closing the opening between the two legs and for retaining the swiveling leg in place.

8. A clevis assembly, comprising: two legs, one of which is adapted to be swivelly inserted in a hole on a drag-bucket (not claimed); a U in the other leg, for the reception of a cooperating chain-link (not claimed); a projection, in co

operation with the forward edge of the bucket for positively confining this link to a position substantially nearer the level of one end of the swiveling portion than of the other end; and 5 means for simultaneously closing the opening between the two legs and for retaining the swiveling leg in place; the clevis being further characterized by the fact that a portion of it will 10 underlie the cooperating portion of the bucket to take the ground-engaging wear.

9. A clevis plate for a drag-bucket, comprising: a projecting lug, containing a substantially vertical hole; two flat portions to straddle the side plate (not claimed) of the bucket, said flat portions being completely separated from each other throughout so much of them as lies rearwardly of the hole by a slot; and at least one projection 15 extending inwardly from one of the flat portions so as to bear against the front edge of the side 0 plate.

10. Means for attaching the drag chain to a drag-bucket, comprising: a clevis plate projecting forwardly from the side of the bucket, and having a cylindrical substantially vertical hole, two flat 5 portions to straddle the side-plate of the bucket, a slot extending rearwardly from the hole where-

by the two flat portions are completely separated from each other throughout, and at least one substantially flat abutment bearing against the front edge of the side-plate; and a clevis assembly, having a cylindrical portion insertable in 5 said hole for swiveling therein, means to secure this portion in place, a transverse hole for engagement with the drag chain, and means to positively confine the chain against vertical shifting while in this last-named hole; the last-named 10 hole being so located in the assembly that a reversal of the assembly will move the hole to a materially different level with respect to the bucket.

11. A clevis plate for a drag-bucket, comprising: a projecting lug, containing a substantially vertical hole; two flat portions to straddle the side plate (not claimed) of the bucket, said flat portions being completely separated from each other throughout so much of them as lies rearwardly of the hole by a slot; and at least one projection 15 extending inwardly from one of the flat portions so as to bear against the front edge 20 of the side plate.

GEORGE W. MORK. 25
